UNITED STATES PATENT OFFICE.

HENRY O. SCHMIDT, OF NEW YORK, N. Y., ASSIGNOR TO THE LANDERS, FRARY & CLARK, OF NEW BRITAIN, CONNECTICUT.

DESIGN FOR A CAP FOR CUTLERY-HANDLES.

SPECIFICATION forming part of Design No. 25,270, dated March 24, 1896.

Application filed February 20, 1896. Serial No. 580,133. Term of patent 7 years.

To all whom it may concern:

Be it known that I, HENRY O. SCHMIDT, a citizen of the United States, residing at New York, in the county of New York and State of New York, have invented and produced a new and original Design for a Cap for Cutlery-Handles, of which the following is a specification, reference being had to the accompanying drawings, in which—

10. Figure 1 is a face or front view of a cap for the butts of cutlery-handles, showing my design. Fig. 2 is an edge view of the same.

The cap is of an oval form in face or front view and is ornamented by an oval series of 15 curved figures, in relief, surrounding an open field.

The edge 3 of the cap is slightly beveled,

as shown, and the face of the cap is nearly flat for a short distance from the edge inwardly, while the middle portion, that forms 20 the open field 4, is rounded so as to project, as shown by the edge view, Fig. 2. On the flat portion and surrounding the oval and open central field 4 is a series of abruptly-curved ornaments 5, abutting against each 25 other, all as shown.

What I claim is—

The design for a cap for cutlery-handles substantially as shown and described.

HENRY O. SCHMIDT.
